SELF-STICKING POCKET CLIP

Ralph N. Karlsen, Warroad, Minn. 56763

Filed May 2, 1974, Ser. No. 466,147

Term of patent 14 years

Int. Cl. D2—07

U.S. Cl. D2—428

FIG. 1

FIG. 2

FIG. 3

FIG. 4

FIG. 5

FIG. 1 is a view in perspective of a self-sticking pocket clip showing my new design;

FIG. 2 is a view in perspective as seen from the opposite side of FIG. 1;

FIG. 3 is a view in side elevation;

FIG. 4 is a view in top plan; and

FIG. 5 is a view in bottom plan.

I claim:

The ornamental design for a self-sticking pocket clip, as shown.
